DESIGN FOR A COMBINED PANEL, OVEN HEAT INDICATOR AND CONTROL KNOB FOR RANGES OR THE LIKE

Herbert M. Reeves, Kankakee, Ill., assignor to
Florence Stove Company, Gardner, Mass., a
corporation of Massachusetts

Application April 15, 1941, Serial No. 100,386

Term of patent 3½ years

To all whom it may concern:

Be it known that I, Herbert M. Reeves, a citizen of the United States of America, residing at Kankakee, in the county of Kankakee and State of Illinois, have invented a new, original, and ornamental Design for a Combined Panel, Oven Heat Indicator and Control Knob for Ranges or the like, of which the following is a specification, reference being had to the accompanying drawing, forming a part thereof.

Fig. 1 is a front elevational view of a combined panel, oven heat indicator and control knob for ranges or the like embodying my new design.

Figs. 2 and 3 are sectional views taken substantially along the lines 2—2 and 3—3, respectively, of Fig. 1.

The dominant features of the design reside in the portions shown in full lines.

I claim:

The ornamental design for a combined panel, oven heat indicator and control knob for ranges or the like, substantially as shown and described.

HERBERT M. REEVES.
